BULLDOZER TRACTOR

Charles H. Herr, Jr., Springfield, Ill., assignor to Allis-Chalmers Manufacturing Company, Milwaukee, Wis.

Application May 5, 1951, Serial No. 224,717

6 Claims. (Cl. 37—144)

The invention relates to excavating machines, and it is concerned more particularly with a self-propelled earth moving machine of the type variously known as a trail builder, backfiller, or bulldozer.

During the past, the prevalent practice of constructing earth moving machines of the above mentioned character has been to adapt or convert a crawler tractor of available general utility type to the intended use although it has also been suggested to provide a specially constructed self-propelled earth handling machine of a more universal character which would be capable not only of pushing dirt, bulldozer fashion, but also of performing other operations such as loading a quantity of dirt into a scraper bowl and transporting the loaded bowl from one place to another.

While it would be difficult, if not impossible, to convert an existing crawler tractor of general utility type into a multiple purpose machine, such as a combined self-loading scraper and bulldozer, the practice of converting an available crawler tractor of general utility type into a bulldozer is quite common, and a great number of attachments have heretofore been suggested for that purpose. Such conversion attachments usually provide a pair of bulldozer push beams which are to be pivoted on the track frames of the tractor, preferably at centers in proximity to the rear drive sprockets, and a lift mechanism for raising and lowering the push beams, the lift mechanism, in some cases, being designed for mounting on the tractor main body, and in other cases for mounting on the track frames.

Space limitations imposed by prevalent crawler tractor designs make it necessary, as a rule, to place the bulldozer push beams outside of the track frames, and where this is done it is usually also necessary to employ a relatively wide bulldozer blade, that is, a blade which is substantially wider than the tread width of the tractor measured between the outside edges of the track belts.

Under certain conditions or special circumstances the width of the bulldozer blade which is necessitated by the outside arrangement of the push beams, may be greater than practical or desirable. For instance, the horsepower capacity of the tractor may not be sufficient to handle as wide a blade as must be used because of the outside push beams; or it may be desired from an engineering and performance standpoint, as well as for reasons of economy, to save as much weight and material as possible; or the machine may be intended for use as airborne equipment by the armed forces; in all of which cases a blade not materially wider than the tread width of the tractor, measured between the outside edges of the track belts, would be desirable.

In order to take care of special situations such as those mentioned hereinbefore, in which a blade of relatively narrow width would be required or desirable, certain types of conversion attachments have heretofore been proposed which incorporate a pair of inside push beams in lieu of the prevalent outside push beams, that is, push beams which extend longitudinally of the tractor in the spaces

2

between the main body and the track frames. However, it is believed that such inside push beam attachments which have heretofore been suggested in order to permit use of a blade not materially wider than the tread spacing of the tractor have not been entirely satisfactory, particularly in the matter of mounting and adjusting the blade on the tractor, and also in the matter of providing a weight saving and economical construction.

Generally, it is an object of the present invention to provide improved equipment for converting an available crawler tractor of general utility type into a material moving machine, and more particularly into a bulldozer tractor having a blade not materially wider than the tread width of the tractor measured between the outside edges of the track belts.

Another object of the invention is to provide an improved narrow blade bulldozer tractor of the hereinabove outlined character which will take care of the matter of proper blade mounting and adjustment, and provide a weight saving and economical construction in a simple, economical and otherwise entirely satisfactory manner.

In the construction and manufacture of crawler tractors for general utility purposes it is usual to employ the well known three-point suspension principle, that is, to connect the main body and track frames for relative up and down swinging movement on a rearward transverse axis, and to support the overhanging forward part of the tractor main body on an equalizer bar, usually in the form of a transverse leaf spring, which is pivoted at its center on the tractor main body and which rests at its opposite ends on forward portions of the track frames.

A further and important object of the invention is to provide an improved method of converting a three-point suspension tractor, that is, a tractor originally equipped with an equalizer bar, into a bulldozer tractor. Such improved method of conversion, as contemplated by the invention, involves elimination of the original equalizer bar and installation of a substitute mechanism which will be operable, under control of the operator, to maintain the tractor main body in selected positions of pivotal adjustment on the mentioned rearward axis.

A further object of the invention is to provide an improved bulldozer tractor which will be less front heavy and afford better visibility from the operator's station than heretofore known bulldozer tractors which are composed of a crawler tractor and conversion attachment of conventional construction.

These and other objects and advantages are attained by the present invention, various novel features of which will be apparent from the description herein and accompanying drawings disclosing an embodiment of the invention, and will be more particularly pointed out in the appended claims.

In the drawings:

Fig. 1 is a side view of a bulldozer tractor embodying the invention;

Fig. 2 is a top view of the bulldozer tractor shown in Fig. 1, Fig. 2 including a diagrammatic outline of hydraulic conduits not shown in Fig. 1;

Figs. 3 and 4 are views similar to Fig. 1 and showing the machine in different conditions of adjustment;

Fig. 5 is a somewhat diagrammatic top view of conventional tractor parts shown in Figs. 1 to 4, and of a conventional transverse leaf spring which forms part of the tractor as normally available for general utility purposes but which according to the present invention, is omitted for conversion purposes as will appear more fully hereinbelow;

Figs. 6, 7 and 8 are side, front and top views, respectively, of the forward end of the tractor main body shown in Fig. 5;

Fig. 9 is an enlarged side view of bulldozer parts shown in Fig. 1 and of parts on the tractor main body to which the bulldozer parts are connected;

Fig. 10 is a top view of the parts shown in Fig. 9;

Fig. 11 is a section on line XI—XI of Fig. 10;

Fig. 12 is a section on line XII—XII of Fig. 9;

Fig. 13 is a section on line XIII—XIII of Fig. 9;

Fig. 14 is a detail view of a transverse mounting wing appearing in Fig. 13; and

Figs. 15 to 18, inclusive, are diagrammatic views of a hydraulic system incorporated in the tractor bulldozer as shown in Figs. 1 and 2.

Referring to Figs. 1 and 2, a tractor main body generally designated by the reference character 1, and a pair of self-laying track units generally designated by the reference characters 2 and 3, respectively, are connected in conventional manner for relative up and down swinging movement on a rearward transverse axis which is indicated in Fig. 2 by the dash-dotted line A—A and which coincides with the axis of rotation of a pair of rear track belt drive sprockets 4 and 6. The tractor main body 1 is of conventional construction and comprises a pair of parallel, transversely spaced side sills or beam elements 7 and 8, and a rearward steering clutch and final drive housing 9. A tractor engine 11 is located at a forward part of the tractor main body and is mounted in the space between the side sills 7 and 8 in the usual manner. An operator's station located on the tractor main body rearwardly of the engine comprises an operator's seat 12 with a back rest 13 and arm rests 14. A large fuel tank 16 for the engine is mounted at the rear end of the tractor main body, and an engine radiator and enclosing shell 17 are mounted at the front end of the tractor main body in conformity with well known and generally accepted engineering principles. A bonnet 18 is mounted over the engine 11 on the radiator shell 17 and on a dash panel 19 in the usual manner.

The steering clutch and final drive gear housing 9 encloses the usual mechanism for transmitting power from the engine 11 to the track belt drive sprockets 4 and 6. Such mechanism is generally indicated in dotted lines in Fig. 2, and includes the customary bevel gear drive designated by the reference character 21, a pair of steering clutches designated by the reference characters 22, and two final drive gear trains designated by the reference characters 23. Fig. 2 also shows the usual steering levers 24, brake pedals 26 and gear shift lever 27 in front of the operator's seat 12.

A cross frame member or basket 28 shown in Figs. 1 and 5 extends between the side sills 7 and 8 and forms a conventional part of the tractor main body. Ordinarily, that is, when the tractor is used for general utility purposes, a transverse equalizer spring 29 is pivotally mounted on the basket by means of a longitudinal pivot pin 31, as indicated in Fig. 5. In the tractor bulldozer as shown in Figs. 1 and 2, tractor main body 1 includes the basket 28, but the equalizer spring 29 and the pivot pin 31 are omitted, and a substitute mechanism is provided, as will be more fully explained hereinbelow, for establishing a load transmitting connection between the tractor main body and the track units 2 and 3 forwardly of the axis A—A.

The self-laying track units 2 and 3, like the tractor main body 1, are of conventional construction and are connected with the tractor main body 1 for swinging movement relative to the latter and relative to each other on the axis A—A. As shown in Fig. 5, the self-laying track unit 2 at the left side of the tractor comprises a rigid track frame including outer and inner side channels 32 and 33 and a rearwardly and inwardly extending diagonal brace arm 34. An outboard bearing 36 at the rear end of the side channel 32, and an inboard bearing 37 at the rear end of the diagonal brace arm 34 are aligned on the axis A—A and cooperate with aligned shaft elements 38 and 39, respectively, on the main body to secure

the left track frame for up and down swinging movement relative to the tractor main body. A front idler 41 and track rollers, not shown, are mounted on the track frame side channels 32 and 33 for cooperation with an endless track belt 42 in the usual manner.

The foregoing explanations with respect to the self-laying track unit 2 at the left side of the tractor, analogously apply to the self-laying track unit 3 at the right side of the tractor, the terms "left" and "right" being used in conformity with the orientation of an operator occupying a forwardly facing position on the seat 12. The reference characters which are applied in Fig. 5 to the self-laying track unit 2 at the left side of the tractor are repeated in the same figure, with primes added, to designate corresponding parts of the self-laying track unit 3 at the right of the tractor.

A material moving tool in the form of a bulldozer is mounted, as generally indicated in Figs. 1 and 2, on the forward part of the tractor main body so as to permit movement of the bulldozer cutting edge into and out of the ground at the forward end of the tractor by downward and upward swinging movements, respectively, of the bulldozer structure in unison with the tractor main body on the axis A—A. In the condition of the machine as shown in Fig. 1, the bulldozer cutting edge is raised a relatively short distance above the ground level which is indicated by the line B—B. Fig. 3 shows the bulldozer and tractor main body swung upwardly on the axis A—A from the position shown in Fig. 2, the bulldozer cutting edge in Fig. 3 being raised to a maximum elevation above the ground level B—B. Fig. 4 shows the bulldozer and tractor main body swung downwardly on the axis A—A from the position shown in Fig. 1, the bulldozer cutting edge in Fig. 4 being lowered to a maximum depth below the ground level B—B.

The details of the bulldozer structure and the connections by means of which the bulldozer structure is rigidly secured to the tractor main body are best illustrated by Figs. 8 to 14. Referring to these figures, and more particularly to Fig. 11, a bulldozer blade 43 of plate metal is bent into the usual arcuate shape to present a concavely curved front face 44 and a convexly curved rear face 46. A cross strip 47 along the lower part of the front face 44 affords a bulldozer cutting edge 48. At the rear of the blade 43, a number of cross members extend longitudinally between the opposite ends of the blade and are welded to the rear face 46 of the latter. One of these cross members presents a vertical wall 49, a horizontal top flange 51 and a forwardly and downwardly inclined bottom flange 52. A transverse mounting wing 53 which is separately shown in Fig. 14, is connected by welding with the wall 49 at the junction of the latter with the top flange 51, and as shown in Figs. 11 and 13, the mounting wing 53 extends in a vertical plane and upwardly from the top flange 51.

A longitudinal mounting wing 54, best shown in side elevation in Fig. 9 and in section in Fig. 13, extends in a vertical plane at right angles to the plane of the transverse mounting wing 53, and at the laterally outer side of the main frame side sill 7, as best shown in Figs. 10 and 12. At its forward end the longitudinal mounting wing 54 has a vertical edge, part of which abuts the wall 49 and another part of which abuts the rear face of the transverse mounting wing 53. Welded seams along the vertical front edge of the longitudinal mounting wing 54 connect the latter with the wall 54 and with the transverse mounting wing 53. As best shown in Fig. 13, the longitudinal mounting wing 54 has a laterally outward extending top flange 56 and a laterally inward extending bottom flange 57, and a triangular gusset plate 58, best shown in Fig. 10, is welded along one edge to the top flange 56 of the longitudinal mounting wing 54 at a forward part of the latter, and another portion of the triangular gusset plate 58 is welded to an edge portion 59 (Fig. 14) of the transverse mounting wing 53, the edge portion 59 extending in

a downwardly inclined direction toward the left end of the bulldozer blade and terminating at a vertical web 61 which is welded to and extends rearwardly from the convex rear face 46 of the blade 43. Another triangular gusset plate 62 (Fig. 13) is welded to the bottom flange 57 of the longitudinal mounting wing 54 at a forward portion of the latter, and to the flange 52 which extends forwardly and downwardly from the vertical wall 49, as shown in Fig. 11.

At the rear end of the longitudinal mounting wing 54, 10 an end plate 63 is secured on edge to the latter so as to extend in a vertical plane and laterally outward from the wing 54, as shown in Figs. 9 and 12. The upper part of the end plate 63 extends vertically beyond the top flange 56 of the wing 54, and a vertical corner plate 64 15 is welded to the upwardly projecting part of the end plate 63 and to the top flange 56 of the longitudinal mounting wing 54 at the rear end of the latter.

For the purpose of mounting the bulldozer structure on the tractor main frame, a bracket plate 66 is secured by welding to the side sill 7 of the tractor main body and at a location rearwardly from the front end of the tractor, as best shown in Fig. 12. The bracket plate 66 is disposed at the laterally outer side of the tractor side sill 7, as shown in Figs. 10 and 12, and has upper and lower parts in vertically upward and downward projecting relation, respectively, to the side sill 7. A mounting bolt 67 which extends transversely of the tractor passes through a pair of registering holes in the corner plate 64 of the bulldozer structure and in the upper part of the bracket plate 66. Another mounting bolt 68 which extends transversely of the tractor passes through a pair of registering holes in the mounting wing 54 and in the lower part of the bracket plate 66, as shown in Fig. 12. The bolts 67 and 68 are provided with nuts 69 and 71, respectively, 35 at the inner side of the bracket plate 66, as shown in Fig. 12, and thus provide a readily detachable connection between the longitudinal mounting wing 54 and the bracket plate 66 on the side sill 7 of the tractor main body.

Another pair of vertically spaced mounting bolts 72 and 73 extend through the transverse mounting wing 53 and through a cross plate 74 at the forward end of the tractor main frame, as best shown in Fig. 11. Referring to Figs. 6, 7 and 8, the cross plate 74 forms part of the normal front end construction of the tractor main frame. As shown in Fig. 7, the cross plate 74 is fitted at its opposite ends into channel openings of the side sills 7 and 8, and the plate 74 is joined at its lower edge with a rearwardly and downwardly inclined cross member 76, which also forms part of the normal front end construction of 50 the tractor main frame. The cross plate 74, cross member 76 and side sills 7 and 8 are rigidly and permanently secured together in conventional manner, as by welding, and the entire structure is reinforced by horizontal gusset plates 77 and by vertical gusset plates 78, as indicated in Figs. 6 and 8.

When the tractor is used for general utility purposes, it is normally equipped with a front bumper, not shown, and the front cross plate 74, as normally furnished, has two pairs of vertically spaced bolt holes for mounting 60 the bumper on the tractor main frame, the left pair of these vertically spaced bolt holes being designated in Fig. 7 by the reference character 79, and the right pair being designated by the reference character 81.

The transverse mounting wing 53, as shown in Figs. 13 and 14, has a pair of vertically spaced bolt holes 82 which in the mounted condition of the bulldozer structure register with the bolt holes 79 of the tractor cross plate 74. The bolts 72 and 73, shown in Fig. 11, extend through the registering bolt holes 79 and 82 and are 70 equipped with nuts 83 at the forward side of the transverse mounting wing 53.

Referring to Fig. 2, the bulldozer blade 43 projects laterally in opposite directions from the tractor main body, and the transverse and longitudinal mounting 75

wings 53 and 53' which have been described hereinbefore serve to connect the left part of the bulldozer blade with the tractor main frame. A corresponding arrangement of transverse and longitudinal mounting wings or mounting portions is provided to connect the right half of the bulldozer blade with the tractor main body, and the reference characters which are applied in Fig. 2 to the transverse and longitudinal mounting wings and associated parts at the left side of the tractor are repeated in the same figure, with primes added, to designate corresponding parts at the right side of the tractor. The right transverse mounting wing 53' has a pair of vertically spaced bolt holes, which in the mounted condition of the bulldozer, register with the vertically spaced bolt holes 81 of the tractor cross plate 74, shown in Fig. 7, and longitudinally extending mounting bolts 72' which correspond to the longitudinally extending bolts 72 and 73 in Fig. 11, extend through the bolt holes 81 of the tractor cross plate 74 and through the registering bolt holes of the transverse mounting wing 53'.

The spaces between the convex rear face 46 of the bulldozer blade 43 and the front faces of the transverse mounting wings 53, 53' are closed by a channel shaped cover strip 75 which extends longitudinally of the blade and is detachably secured in place by a bolt 80 at the left end of the cover strip, as shown in Figs. 10, 11 and 13, and by a corresponding bolt, not shown, at the right end of the strip 75. As shown in Figs. 10 and 13, the left end of the cover strip 75 rests on and is secured by the bolt 80 to an angle bracket 85 which is fitted between the rear face 46 of the bulldozer blade and the front face of the transverse mounting wing 53, and which angle bracket is permanently secured in place by welding. A corresponding angle bracket, not shown, is provided for the right end of the cover strip 75.

As pointed out hereinbefore, and as illustrated by Figs. 3 and 4, the cutting edge 48 of the bulldozer is movable into and out of the ground at the forward end of the tractor by downward and upward swinging movements, respectively, of the bulldozer structure in unison with the tractor main body on the rearward transverse axis which is indicated by the dash-dotted line A—A in Fig. 2 and which coincides with the axis of the shaft element 38 in Fig. 1. Provisions are made to either prevent or permit unitary pivotal movement of the tractor main body and bulldozer from a bulldozer raised position, as shown for instance in Fig. 3, to a bulldozer lowered position, as shown for instance in Fig. 4, and to effect unitary pivotal movement of the tractor main body and bulldozer from a bulldozer lowered to a bulldozer raised position. To that end, the bulldozer tractor as disclosed herein for purposes of exemplification, is equipped with two lift mechanisms, one at the left side which is best illustrated in Figs. 1 and 2, and the other at the right side, which is substantially a duplicate of the lift mechanism at the left side and which is shown, in top view only, in Fig. 2.

As shown in Figs. 1 and 2, a pair of uprights 84 and 86 are rigidly mounted on the self-laying track unit 2, and are rigidly connected with each other at their upper ends by a channel shaped yoke 87. As shown in Fig. 1, the yoke 87 extends parallel to the track frame side channel 32, and as shown in Fig. 2, the yoke 87 is angularly displaced relative to the longitudinal vertical center plane of the track unit 2 so as to extend obliquely forward toward the left side of the tractor main body. A bellcrank lever 88 has a fulcrum at 89 on the yoke 87, and a hydraulic jack 91 for rocking the lever 88 on its fulcrum 89 comprises a cylinder 92 which is pivoted at 93 on the yoke 87, a piston 94 within the cylinder 92, and a piston rod 96 which is pivoted at 97 to a short arm of the bellcrank lever 88. A stiff link 98 has a ball and socket connection at 99 with a long arm of the bellcrank lever 88, and a ball and socket joint 101 connects the

link 98 with the bulldozer structure, and through the latter with the main body of the tractor.

As best shown in Figs. 9, 10 and 13, a ball element 102 of the ball and socket joint 101 is mounted on a pair 5 of ear plates 103 which are welded to the wall 49 in back of the blade 43, and the ear plates are connected with each other by a brace plate 104 which is welded to the lower edges of the ear plates 103 and to the wall 49.

The lift mechanism at the right of the machine, and which is shown in top view in Fig. 2, comprises a hydraulic jack 91' which is a duplicate of the hydraulic jack 91, a bellcrank lever 88' which is a duplicate of the bellcrank lever 88, and a supporting structure for the jack 91' and bellcrank lever 88', which is rigidly mounted 10 on the swingable track frame of the right self-laying track unit 3. The supporting structure for the jack 91' and bellcrank lever 88' comprises uprights 84', 86' and a yoke 87', corresponding, respectively, to the uprights 84 and 86, and to the yoke 87, but the angular displacement of the yoke 87' is opposite to that of the yoke 87, that is, the yoke 87' extends obliquely forward toward 15 the right side of the tractor main body. A stiff link 98' corresponding to the link 98, is connected at its upper end with the bellcrank lever 88' and at its lower end with the bulldozer structure in the same manner as has been explained hereinbefore in connection with the bellcrank lever 88, link 98, and ball and socket joints 99 and 101. Ear plates 103' at the right end of the bulldozer blade, as shown in Fig. 2, correspond to the ear plates 103 at the left end of the blade, and serve 20 to connect the lower end of the link 98' with the bulldozer structure.

The piston 94 of the hydraulic jack 91 is movable within the cylinder 92 to a rearward limit or bulldozer raised position, as shown in Fig. 3, and to a forward limit or bulldozer lowered position, as shown in Fig. 4. The piston of the hydraulic jack 91' is similarly movable to bulldozer raised and bulldozer lowered positions, and in the condition of the machine as shown in Fig. 3 both pistons are in their bulldozer raised positions, while in the condition of the machine as shown in Fig. 4 both pistons are in their bulldozer lowered positions. The cylinder 92 of the hydraulic jack 91 has a first port 106 at the end at which the piston 94 is located in its bulldozer lowered position (Fig. 4) and the cylinder 92' of the hydraulic jack 91' similarly has a first port 106' at the end at which the piston of the jack 91' is located in its bulldozer lowered position. Second ports 107 and 107' are formed at the ends of the cylinders 92 and 92', respectively, at which the pistons of the hydraulic jacks are located in their bulldozer raised positions. The first ports 106 and 106' are connected with each other by a conduit 108 which has a branch 109 connected with a first discharge port 111 of a valve mechanism 112 at the right side of the tractor as shown in Fig. 2. The second cylinder ports 107, 107' are connected with each other by a conduit 113 which has a branch 114 in communication with a second discharge port 116 of the valve mechanism 112.

The conduits 108 and 113 together with their branches 109 and 114, respectively, and the valve mechanism 112 are part of a hydraulic system which is diagrammatically illustrated in various operating conditions by Figs. 15 to 18. Referring to Fig. 15, the hydraulic system is supplied with pressure fluid by a pump P which is driven by the tractor engine 11 in any suitable manner (not shown), and at its inlet or suction side the pump P draws a suitable liquid, such as oil, from a reservoir 117 which is diagrammatically indicated in Fig. 15 and which is shown in Fig. 2 in the form of a tank at the right side of the tractor. The valve mechanism 112 is of a well known construction which is commonly used in connection with hydraulically operated tractor bulldozers. As diagrammatically indicated in Fig. 15, a rotatable valve body 118 and a reciprocable valve body 119 are mounted

6 in a valve housing 121 which, in addition to the mentioned first and second discharge ports 111 and 116, has an inlet port 122 in communication with the discharge side of the pump P, and an outlet port 123 in communication with the reservoir 117.

Fig. 15 shows the hydraulic system in a "hold" condition in which the discharge of the pump P is directed through the rotatable valve body 118 directly into the outlet port 123 and reservoir 117, while escape of fluid 10 from the forward cylinder spaces 124, 124' is prevented by the reciprocable valve body 119, and escape of pressure fluid from the rearward cylinder spaces 126, 126' is prevented by a land 127 of the rotatable valve body 118. The pistons 94 and 94' are shown in Fig. 15 in positions midway of their forward and rearward limit 15 positions, corresponding to the position in which the piston 94 is shown in Fig. 1. In the "hold" position of the hydraulic system, as shown in Fig. 15, the tractor main body 1 together with the bulldozer structure are prevented from downward swinging movement on the rearward axis A—A and also from upward swinging movement on said axis, but the track units 2 and 3 are capable of controlled swinging movement, in opposite 20 directions, relative to the tractor main body. For instance, the self-laying track unit 2 at the left side of the tractor may swing upward, and as a result pressure fluid will be displaced from the forward cylinder space 124 (Fig. 15) of the jack 91 into the forward cylinder space 124' through the conduit 108. As the cylinder 92' of the jack 91 moves forward, while the cylinder 92 of the jack 91 moves rearward in response to upward 25 swinging movement of the left track unit 2, the track unit 3 at the right side of the tractor will be swung downward on the axis A—A while the track unit 2 at the left side of the tractor swings upward on said axis. Analogously, if the left track unit 2 swings downward, pressure fluid will be displaced from the rearward cylinder space 126 of the jack 91 into the rearward cylinder space 126' of the jack 91' through the conduit 113, with the 30 result that the right track unit 3 is swung upward on the rearward pivot axis A—A relative to the tractor main body 1 while the left track unit 2 swings downward on said axis. In either case, the angular displacement of one track unit from its horizontal position in one direction will be the same as the angular displacement of the other track unit from its horizontal position in the opposite direction. During any transfer of pressure fluid from one of the forward cylinder spaces 124 and 124' to the other, a corresponding transfer of pressure fluid 35 in the opposite direction will take place between the rearward cylinder spaces 126, 126' through the conduit 113. But there can be no transfer of pressure fluid from either or both of the forward cylinder spaces to one or both of the rearward cylinder spaces as long as the valve mechanism 112 is in the hold condition, in which it is shown in Fig. 15. In other words, in the hold condition of the valve mechanism, the tractor main body and the bulldozer structure are prevented from unitary pivotal movement on the axis A—A in bulldozer lowering direction, and also in bulldozer raising direction.

Fig. 16 shows the hydraulic system in a "raise" condition in which the discharge of pump P is directed through the rotatable valve body 118 into a passage 128 of the valve housing 121, and from which passage the pressure fluid may pass to the discharge port 111 past the reciprocable valve body 119. A coil spring 129 normally tends to force the valve body 119 upon its seat, but yields to the pressure of the pump P to let pressure fluid pass from the passage 128 to the discharge port 111 40 and from the latter through the branch conduit 109 and through the conduit 108 into both forward cylinder spaces 124 and 124'. The rearward cylinder spaces 126 and 126' communicate through the conduit 113, branch 114 and through passages 131 and 132 of the valve housing 45 with the outlet port 123, while the valve mechanism 70

75

is in the "raised" position as shown in Fig. 16. Admission of pressure fluid simultaneously into both forward cylinder spaces 124 and 124', as shown in Fig. 16, causes swinging movement of the tractor main body and bulldozer structure in bulldozer raising direction, while pressure fluid is being emitted from the rearward cylinder spaces 126 and 126', through the conduits 113, 114 into passage 131 and from the latter past the rotary valve body 118 into passage 132, outlet 123 and reservoir 117.

Fig. 17 shows the hydraulic system in a "lower" condition in which the discharge of the pump P is directed through the rotatable valve body 118 into the passage 131 of the valve housing 121, while the reciprocable valve body 119 is held in an open position by the land 127 of the rotatable valve body 118. As a result, pressure fluid will be admitted into the rearward cylinder spaces 126, 126', and at the same time pressure fluid will be emitted from the forward cylinder spaces 124 and 124' through the conduit 108, branch 109, discharge port 111 and past the valve body 119 into the passage 128 of the valve housing and from the latter, past the valve body 118 into an internal passage 133 of the valve housing, which in turn communicates through the outlet port 123 with the reservoir 117. Upon adjustment of the valve mechanism to the condition shown in Fig. 17, the weight of the tractor main body and of the bulldozer structure will no longer be supported by the hydraulic jacks 91 and 91' because the pressure fluid from the forward cylinder spaces 124 and 124' will freely escape into the reservoir 117, as has been explained hereinbefore. Accordingly, the tractor main body will swing downwardly under its own weight and under the weight of the bulldozer structure until the bulldozer cutting edge 48 comes to rest on the ground and prevents further downward movement of the tractor main body and bulldozer structure. Application of fluid pressure to the rearward cylinder spaces 126, 126' while the cutting edge 48 rests on the ground will tend to swing the track units 2 and 3 upwardly about the transverse rear axis A—A, and as a result part of the weight of the track units will be added to the downward load which tends to force the cutting edge 48 into the ground.

Fig. 18 shows the hydraulic system in a "float" condition in which the discharge of the pump P is directed through the rotatable valve body 118 and through the passage 132 of the valve housing to the discharge port 123, and in which the forward cylinder spaces 124 and 124' and the rearward spaces 126 and 126' also communicate with the outlet port 123 of the valve body 121. As shown in Fig. 18, the reciprocable valve body 119 is kept open by the land 127 on the rotatable valve body 118 and the passage 128 of the valve housing communicates with the passage 133 which in turn communicates with the outlet 123. On the other hand, the passage 131 of the valve housing 121 is placed into communication with the outlet port 123 by adjustment of the rotary valve body 118 to the position in which it is shown in Fig. 18. In the float condition of the hydraulic system, as shown in Fig. 18, the cutting edge 48 of the bulldozer rests on the ground, and the tractor main body and the bulldozer structure may move to any position of pivotal adjustment on the axis A—A without impediment by the hydraulic jacks 91 and 91' within the limits of back and forth movement of the pistons 94 and 94' within the cylinders 92 and 92', respectively.

The herein disclosed bulldozer tractor accomplishes the objects outlined hereinbefore. That is, it can readily be constructed by converting an existing crawler tractor of general utility type, and more particularly a crawler tractor of the three point suspension type as shown in Fig. 5, into a bulldozer tractor as shown in Figs. 1 and 2. This may be done, as explained in detail hereinbefore, by securing a bulldozer structure in fixed position to the main body of the tractor, and by substituting for the conventional equalizer bar, an operator controlled mecha-

nism which either prevents unitary pivotal movement of the tractor main body and bulldozer from a bulldozer raised to a bulldozer lowered position, for instance in the manner explained hereinbefore in connection with Fig. 15, or which permits such unitary pivotal movement, for instance in the manner explained hereinbefore in connection with Fig. 17, or which may effect unitary pivotal movement of the tractor main body and bulldozer from a bulldozer lowered to a bulldozer raised position, for instance as explained hereinbefore in connection with Fig. 16. It is not necessary that the bulldozer blade be materially wider than the tread width of the tractor, the width of the blade 43, as shown in Fig. 2, being substantially the same as the tread width of the tractor measured between the outside edges of the track belts. The blade mounting is not only space saving, sturdy and compact, but it is also simple and of a character which makes its adoption desirable where light weight and low costs are required. When the machine is in digging position, as shown in Fig. 4, forward visibility from the operator's station at the rear is improved due to the considerable lowering of the forward part of the tractor main body and its associated radiator shell 17, bonnet 18 and dash panel 19, relative to the operator's eye level which remains substantially unchanged when the tractor body is swung downwardly from the horizontal position shown in Fig. 1 to a digging position such as shown in Fig. 4. The converted tractor is not unduly front heavy and therefore can be operated to cut at a relatively great depth below the ground level without danger of tipping over or imposing an excessive load on the front idlers of the self-laying track units.

It should be understood that it is not intended to limit the invention to the particular form and details described hereinbefore, and that the invention includes such other forms and modifications as are embraced by the scope of the appended claims.

It is claimed and desired to secure by Letters Patent:

1. In an excavating machine comprising a crawler tractor and a bulldozer connected therewith, the combination of, a pair of transversely spaced beam elements forming side members of the main body of said crawler tractor, a tractor engine mounted between said beam elements at a forward part of said tractor main body, a housing structure forming a rear part of said tractor main body and rigidly secured to the rear ends of said beam elements, a pair of self-laying track units having rearward pivot connections, respectively, with said housing structure on a transverse horizontal axis, means including power transmitting mechanism enclosed within said housing structure for connecting said self-laying track units in driven relation with said tractor engine; a blade member of said bulldozer presenting concavely and convexly curved front and rear faces, respectively; mounting wings rigidly connected with said blade member at said convexly curved rear face thereof; connecting means including said mounting wings rigidly securing said bulldozer on and in depending relation to said beam elements so as to permit movement of the cutting edge of said bulldozer blade into and out of the ground at the forward end of said tractor by downward and upward swinging movements, respectively, of said bulldozer in unison with said tractor main body on said transverse axis; and means selectively operable to either prevent or permit unitary pivotal movement of said tractor main body and bulldozer on said axis from a bulldozer raised to a bulldozer lowered position, and to effect unitary pivotal movement of said tractor main body and bulldozer on said axis from a bulldozer lowered to a bulldozer raised position.
2. In an excavating machine as set forth in claim 1, the combination of a pair of transverse mounting wings extending crosswise of said beam elements and rigidly connected with said bulldozer blade at said convexly curved rear face of the latter, and means including bolts

11

extending longitudinally of said tractor through said transverse mounting wings for detachably securing said bulldozer to said beam elements.

3. In an excavating machine as set forth in claim 1, the combination of a pair of longitudinal mounting wings rigidly connected with said bulldozer blade at said convexly curved rear face of the latter and in transversely spaced relation to each other so that said longitudinal mounting wings overlap the laterally outer sides, respectively, of said beam elements, brackets secured, respectively, to said beam elements, and means including bolts cooperable with said brackets and with said longitudinal mounting wings for detachably securing said bulldozer to said tractor main body.

4. In an excavating machine as set forth in claim 1, the combination of a pair of transverse mounting wings and a pair of longitudinal mounting wings rigidly connected with said bulldozer blade at said convexly curved rear face of the latter, and means including bolts extending longitudinally of said tractor through said transverse mounting wings, and bolts extending transversely of said tractor through said longitudinal mounting wings, for detachably securing said bulldozer to said beam elements.

5. An excavating tractor comprising in combination: a main frame having a rear final drive housing and a pair of laterally spaced parallel push beams fixedly secured at their rearward ends to said housing to form a rigid unitary structure; a pair of self-laying track units pivotally connected at their rearward ends to opposite lateral sides, respectively, of said final drive housing for independent vertical swinging movement relative to said main frame and each other about a transverse axis, said track units being disposed on laterally outward sides of said push beams, respectively, in parallel relation to the latter; an engine for driving said track units mounted on forward portions of said push beams in proximate transverse alignment with forward portions of said track units; a bulldozer structure fixedly secured to said push beams for movement therewith, said bulldozer structure including a transversely disposed blade positioned forwardly of and adjacent to said engine and extending laterally in front of said track units; a double acting hydraulic jack at each side of said main frame operatively interposed between the latter and the adjacent track unit for raising and lowering said blade by vertically swinging said main frame relative to said track units about said transverse axis; and hydraulic pressure means for actuating said jack including equalizing fluid connections between corresponding ends of said jack to afford relative vertical swinging movement between said track units without imparting vertical swinging movement to said main frame, said jacks upon actuation in one direction by said pressure means being operative to swing said main frame downwardly and transfer weight from said track units to said main frame to urge the cutting edge of said blade downwardly into material being excavated.

12

tween corresponding ends of said jacks to afford relative vertical swinging movement between said track units without imparting vertical swinging movement to said main frame, said jacks upon actuation in one direction by said pressure means being operative to swing said main frame downwardly and transfer weight from said track units to said main frame to urge the cutting edge of said blade downwardly into material being excavated.

6. An excavating tractor comprising in combination: 10 a rigid unitary main frame including a final drive housing at the rearward portion of said main frame; a pair of self-laying track units pivotally connected at the rearward end to opposite lateral sides, respectively, of said final drive housing for independent vertical swinging movement relative to said main frame and each other about a transverse axis, said track units being disposed on laterally outward sides of said main frame respectively; an engine for driving said track units mounted on said main frame forward of said final drive housing; a bulldozer structure fixedly secured to said main frame for movement therewith, said bulldozer structure including a transversely disposed blade positioned forwardly of said engine and extending laterally in front of said track units; a double acting hydraulic jack at each side 25 of said main frame operatively interposed between the latter and the adjacent track unit for raising and lowering said blade by vertically swinging said main frame relative to said track units about said transverse axis; and a hydraulic pressure means for actuating said jack including equalizing fluid connections between corresponding ends 30 of said jack to afford relative vertical swinging movement between said track units without imparting vertical swinging movement to said main frame, said jacks upon actuation in one direction by said pressure means being operative to swing said main frame downwardly and transfer weight from said track units to said main frame to urge the cutting edge of said blade downwardly into material being excavated.
